(57) **CLAIM**

The ornamental design for an applicator clip for applying a hair composition to a bundle of hair strands, as shown and described.

DESCRIPTION

FIG. 1 is a perspective view of our new design shown in a closed position, the design being capable of being in an open or closed position;

FIG. 2 is a front view;

FIG. 3 is a rear view;

FIG. 4 is a left side;

FIG. 5 is a bottom view; and,

FIG. 6 is a bottom perspective view.

Wherein the shaded portions of FIGS. 1-6 represent a contrasting color to the non-shaded portions of FIGS. 1-6, and wherein the broken lines represent disclaimed portions of the design.
